(57) **CLAIM**

The ornamental design for a tapeless measuring gauge, as shown and described.

DESCRIPTION

FIG. 1 is a top, rear and left side perspective view of a tapeless measuring gauge showing my new design; FIG. 2 is a bottom, front and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" framed in FIG. 1.

The broken lines show portions of the tapeless measuring gauge that form no part of the claimed design. In FIG. 1 and FIG. 9, a broken line rectangular frame defines the boundary of an enlarged view and form no part of the claimed design.
